UNITED STATES PATENT OFFICE

165,503

TOY JET PROPELLED BOAT

Nino Barsotti, Pittsburgh, Pa.

Application July 26, 1949, Serial No. 4,140

Term of patent 3½ years

(Cl. D34—15)

To all whom it may concern:

Be it known that I, Nino Barsotti, a citizen of the United States, residing at the city of Pittsburgh, in the county of Allegheny and State of Pennsylvania, have invented a new, original, and ornamental Design for a Toy Jet Propelled Boat, of which the following is a specification, reference being had to the accompanying drawing, forming part thereof, wherein:

Fig. 1 is a perspective view of a toy jet propelled boat, showing my new design, and

Fig. 2 is a side view of the same.

I claim:

The ornamental design for a toy jet propelled boat, substantially as shown.

NINO BARSOTTI.
